(57) **CLAIM**

The ornamental design for an inflatable pontoon slide, as shown and described.

DESCRIPTION

FIG. 1 is a front perspective view of an inflatable pontoon slide, showing my new design;

FIG. 2 is a rear perspective view thereof;

FIG. 3 is a front view thereof;

FIG. 4 is a rear view thereof;

FIG. 5 is its enlarged left plan view;

FIG. 6 is its enlarged right plan view;

FIG. 7 is a top view thereof;

FIG. 8 is a bottom view thereof;

FIG. 9 is an enlarged detail view of area 9 in FIG. 1;

FIG. 10 is an enlarged detail view of area 10 in FIG. 1;

FIG. 11 is an enlarged detail view of area 11 in FIG. 1; and,

FIG. 12 is an enlarged detail view of area 12 in FIG. 2.

The dash-dot-dash broken lines in FIGS. 1, 2, and 9-12 depict the bounds of the enlarged views and form no part of the claimed design.

1 Claim, 12 Drawing Sheets
